PROCESS AND MACHINE FOR FILLING
AMPOULESWalter Schaeffer, Frankfort-on-the-Main,
GermanyApplication October 17, 1930, Serial No. 489,463,
and in Germany October 16, 1929

11 Claims. (Cl. 226—75)

In the process of filling, sealing and labeling ampoules, such as are chiefly used for pharmaceutical purposes, the different operations have hitherto been carried out partly by the hand, 5 partly by machines together with manual assistance. A process of mechanically handling and filling great numbers of ampoules with liquid in which nearly all the parts of the work was formerly performed by the hand, such as the cutting 10 off of the necks, the filling, the sterilizing, the closing by melting and the packing up, has been unknown heretofore.

First of all the invention refers to a continuous process, by which the different ampullae are 15 collected on a conveying band and then submitted to the various operations, which are again effected automatically without the assistance of the hand. Manual labor is but occasionally required for the conveyance from one stage of 20 work to the other.

The new process comprises in individually receiving in a conveying band a number of open ampoules from a receptacle filled with empty, 25 open ampoules and are then jammed in by a second band preparatory to the first operation. The latter serves to equalize the necks. The conveying band runs through a glass cutting device and then past a striking contrivance, by which the tops of the necks are cut off, whereupon the 30 bands with the necks of an equal height are wound up on a drum. For the second operation the wound-up conveying band is placed into a container, which should be well stopped up and be provided with a vacuum conduit and an inlet 35 conduit for the filling liquid. Through the vacuum the ampoules are exhausted of air, with the subsequent application of an indifferent gas, so that, after the streaming in of the liquid, they will automatically fill with a certain quantity 40 under the accurately regulated pressure of the streaming. As the ampoules are hanging with their necks downward, there remains above, at the bottom of the ampoules, a layer of air or gas, which is then driven out by centrifuging. 45 After this centrifuging, the band roll is placed on a shaft on another working-table, from which the conveying band will be unwound, while the ampoules are automatically closed by melting and are carried away separately to another container. 50 After being collected there, they are taken, together with the container, to a sterilizing contrivance and afterwards automatically conveyed from the said container to another conveying band, on which they are supplied, also 55 mechanically with inscriptions, labels and the

like. At last the finished ampoules are conveyed by this band to the packing device.

Furthermore, the invention refers to the automatic contrivances appearing in the process described above, such as are required for the operation of the various devices. First there are the devices for the collection, the conveyance, the common treatment in great number and the final delivery of the ampoules. In the course of this treatment, which may be termed "flowing work", 60 the different devices have to be inserted. After their reception by the conveying band, the ampoules come to a cutting device, which cuts all the necks at an equal height, so that they can be struck off by a striking contrivance inserted directly behind the cutting device and moving automatically in accordance with the respective distances of the ampoules. The next device is a drum or a container, on or in which the conveying band is wound up together with 65 the ampoules so as to form a compact roll, which will contain about 600 ampoules, according to the size of the ampoules and the hardiness of the roll with a view to the further operations. 70

By the following operations with the use of such 75 a roll, a great number of ampoules can be simultaneously submitted to the same operation, i. e. to such operations, as, hitherto, could only be effected with separate ampoules and are new in themselves, as e. g. the centrifuging process intended 80 to secure a good filling and the evacuating process for emptying the ampoules.

First the roll is placed into a vacuum container capable of working with indifferent gas 85 and having, beside the usual suction piping, a liquid container connected with it, the liquid which is to be filled into the ampoules with their necks suspended downwardly. By emptying and replenishing the containers repeatedly there will 90 be obtained a definite, equal filling of the ampoules, which may be closed with some indifferent gas, so that the troublesome and time consuming work 95 of an equitable separate filling (pearl filling) is avoided.

The rows of ampoules thus filled are now put 100 into an ordinary centrifugal vessel into which, the plates, rolls, or containers with the ampoules are placed in such a position that the necks are directed toward the axis of the centrifugal shaft, i. e. that the bottom of each ampoule is directed 105 outwardly. By the centrifuging the atmosphere still contained in the body of the ampoule is driven into the necks and then out of the latter, so that now all the ampoules in one roll have 110 a filling of an equal elevation.

In the following operation the roll is again used as a conveying band, a simple contrivance in itself. Along the said band is located the melting device with a preheater, by which the ampoules are automatically closed by melting while passing through, and this device is joined with a contrivance which detaches the ampoules again from the conveying band and takes them to a collecting vessel, which is used for mass sterilization in the ordinary way. The said vessel is arranged in such a manner that the ampoules are delivered separately to another conveying band, on which the inscriptions, labels etc. are fixed automatically on the ampoules.

15 In the subjoined drawings the separate devices for carrying out the process in accordance with the invention are represented.

Fig. 1 shows a top view of the device for the first working stage serving for the reception of the ampoules to be filled and for the cutting of the ampoule necks in the length required.

Fig. 2 is a side view of the supply device for the empty ampoules.

Fig. 3 is a detail (seen in the direction of the arrow A in Fig. 1) of the cutting device.

Fig. 4 the annexed device for striking or breaking off the necks.

In Fig. 5 a piece of strap is shown, which illustrates the way how the different ampoules are received in pouches, while Fig. 6 is the top view corresponding to Fig. 5.

Figs. 7 and 8 show two further eventualities, by way of example, for holding the ampoules in the bearing strap.

35 The second and the third operations are represented in Figs. 9-14:

Figs. 9 and 10 being the top view and the view of a drum with a filled bearing strap.

Fig. 11 shows a vessel with an inserted and filled 40 drum for evacuating and filling the ampoules.

Fig. 12 is the centrifuging device with two filled drums inserted.

Fig. 13 shows a filled ampoule previous to the centrifuging, and Fig. 14 after the latter.

45 The fourth operation is illustrated in Fig. 15, which shows how the ampoules are wound off the filled up bearing strap, how their necks are closed by melting and how they are then filled into a semicircular drum.

50 Fig. 16 shows the view of a detail according to Fig. 15.

Figs. 17-20 illustrate the fifth operation, viz.

Fig. 17 shows the top view of two filled semi-circular drums, composed so as to form a full circle;

Fig. 18 shows a side view and partly a section of a couple of drums with their holder turned over;

60 Fig. 19 is a top view of the same;

Fig. 20 shows how the holder with the filled semi-circular drums is inserted into a closed boiling vessel.

65 The sixth operation is illustrated in Figs. 21-24, viz.:

Fig. 21 shows the side view and the front view of a drum that may be closed;

Fig. 22 shows the side view and a part section of the arrangement of the said drum over the conveying band, while, in connection with this,

70 Fig. 23 shows the top view of the conveying band;

Fig. 24 is a schematic illustration of the conveying device with its stamping contrivance and 75 the delivery of the ready-made ampoules.

Fig. 25 represents the working diagram of the invention.

Fig. 26 shows the packing device.

The empty ampoulae are set by hand into a box 1 in an upright position (Fig. 1 to the right), 80 where they are continually pressed by the slider 2 toward the outlet 3 of the box 1. The said slider 2 receives its motion over the string pulley 4 by the weights 5. In front of the outlet 3 a bearing band 6 is passed before an adjustable 85 guide rail 7 for receiving the empty ampoulae. The band 6 is successively conveyed from the drum 8 over the guide drum 9, past the outlet 3, between the two other guide rollers 10 and 11 lying opposite each other, past the guide roller 12, 90 through a cutting device described below, past another guide drum 13, and between two guide rollers 14 and 15 to the drum 16. The latter drum is driven in any desired manner for winding up the band 6, while the drum 8 is rotated 95 by the tension of band 6 and is equipped with brakes. The band 6 bears separate pouches 17 (Figs. 5, 6, 7 and 8), which hold the ampoulae 19 with their bottoms 18. In order to hinder the ampoulae from falling out of the pouches 17, they 100 are fitted, from the outlet 3, to a fixed guide 20, which is replaced by another band 21 at 22. The said band 21 is wound off the empty drum 23 and runs from 22 together with the band 6 to the drum 16. In this manner the ampoulae are 105 secured between the two bands against falling out of the pouches 17 during the whole course of working. But one band will suffice, provided that the ampoulae are suitably fixed.

The above-mentioned cutting device 24 (Fig. 110 3) cuts the heads of the ampoulae at 27 by means of its cutting edges 25, 26 under the influence of the springs 28, 29. Thence the ampoulae pass to the striking-off device 30 (Fig. 4) and come to lie with their necks before the fixed bow 31 serving 115 for the impact. Opposite this bow is standing a beater 32. The latter is borne by an arm 34 pivoted at 33. A cam drum 35 gives the arm 34 a swinging movement of such a kind that the beater 32 will break off the cut ampoulae necks 120 towards the left over the bow 31. The cutters 25, 26 are adjustable in their height. Accordingly, the striking-off device may be adjusted as well. From here the ampoulae cut off in the length required pass to the drum 16. 125

Instead of holding the ampoulae in the band 6 by means of the band 21 running along with it, there may be provided a fixed ledge, if necessary, from 22 up to the drum 16, in which event a single band will suffice. 130

Another form of the pouches 17 of the band 6 is shown in Figs. 7 and 8. According to Fig. 7, clamps are fitted to the band 6, which resiliently contact the ampoulae with their arms 36. The latter are conically bent outwards at their free 135 ends, in such a manner that the ampoulae may be inserted into the clamps by a slight pressure.

In accordance with the embodiment in Fig. 8 the ampoulae are likewise slipped into clamps. Here the arms 36 are connected resiliently with the band 6 by means of the joints 37. 140

The band 6 filled with the ampoulae rolled up on the drum 16 together with the guide band 21, constitutes the first operation. 145

Thereupon the filled drum 16 is placed into a vessel 38, for the second operation, in such a manner that the ampoulae are positioned with their necks 39 directed downwardly. The vessel 38 thus filled is now set into a container 40 that may be 150

hermetically closed. The liquid to be filled into the ampoules is let into the container 40. By evacuating and re-admitting the normal pressure into the container the ampullae will be filled.

The necks of the ampullae thus filled remain filled with a portion of the liquid, which prevents them from being closed by melting, or will at least render this operation difficult (Fig. 13). By 10 swinging the ampoules in an appropriate centrifugal machine or by evacuating in an upright position it is possible to empty at once the necks of the filled ampullae. For this purpose two filled drums 16 lying opposite each other are inserted 15 into the box of a centrifugal device 41, in such a manner that the necks 39 of the ampullae will be directed toward the axis 42 of shaft 43 of the centrifugal device. The shaft 43 of the centrifugal device should preferably be placed in an 20 upright position. By the centrifuging of the filled ampullae the neck 39 of each ampulla is being substantially freed from liquid. It may be desirable to leave small amounts of liquid in the neck as a seal as shown in Fig. 14.

25 The centrifuged ampullae are set up with their drum 16 on an axle 45 which may be turned in the table 44 (Fig. 15). The filled bands 6 and 21 are thus conveyed past the guide drums 46, 47 and 48 and then between two drums 49 and 50. 30 The axles of the drums 49 and 50 bear at each of the two arms 51 and 52 the adjustable wire bows 53 and 54. The said wire bows are arranged in their height in such a way that the ampullae are passed between them with their necks. From 35 here the band 6 is led to the drum 55 and the band 21 on the drum 56. The said two drums are driven in any desired manner in the direction of the two arrows. When separating the bands, the 40 ampullae are kept with their necks between the wire bows 53 and 54, which strips them from the band 6 and they are thus bound to glide into another guide track 57. The said track consists of 45 two rails, 58 and 59 placed laterally opposite each other and of a foot rail 60 (Fig. 16). On this guide track the ampullae will separately slide along behind each other. A small flame 61 pre-heats the ampullae necks passing through, and the burner 62 with its fine pointed, but somewhat broadened flame closes by melting the necks of 50 the ampullae passing by. In order to avoid a detrimental effect of the liquid and the air on the closing process by melting owing to the warming, cold air is blown through a broadened nozzle 63 against the ampullae at the spot where their 55 necks start. The ampullae now closed by melting leave the guide 57 at 64 and are sliding, always in an upright position, into the box 65. From the latter they are pushed by the hand or 60 mechanically into a semicircular box mould 66, the side wall of which is open at 67.

When two moulds 66 are packed with filled and closed ampullae, these two moulds are placed together as a couple, thus forming a circle (Fig. 17), and a holder 67 is laid over them. Thereupon the said holder 67 is turned upward with its handles 68, so that now the ampullae will stand with their necks on the bottom of this container (Fig. 19), and the semicircular containers are removed, leaving the ampullae standing 70 in a downward direction in the holder 67 with their necks closed by melting. In this manner the ampullae are tested with regard to the seal of the necks simultaneously with the sterilization thereof. Ampullae with defective seals are 75 emptied. For this purpose, as illustrated in Fig.

20, the holder 67 is put into a boiling vessel 69 that may be closed.

For the last turn of work the ampullae are placed into a drum 70 capable of being closed (Fig. 21 and 22), the narrow side of which has at one spot an aperture that may be closed 80 through the slider 72. The drum 70 filled with ampullae is set with its aperture 71 on its edge over the hopper 73. Below the hopper 73 a conveying band 74 is passed by. Now, when the slider 72 leaves the aperture free, the ampullae will fall into the hopper 73 and thence on the conveying band 74. As may be seen from Fig. 23, apertures 75 are provided in the band at certain distances in conformity with the length and breadth of the ampullae. Each time the ampullae will fall into these apertures and are held in the latter through bows fitted under the band. The said bows are shaped in such a manner that the wide bow 76 embraces the body of the ampulla near the bottom, while the bow 77 bears the ampulla at its neck base at 78. The ampullae are located at such a depth in the apertures 75 that about one third of their circumference is 90 projecting above the surface of the band. 100

The band 74 now conveys the ampullae lying in the apertures below the stamping device 79 (Fig. 24). The rotary stamp is moving in the reverse direction to the movement of the conveying band 74, so that the ampullae lying in the bows 76 and 77 can roll below the stamp 79 to be printed. At 80 the ampullae fall out of the apertures of the conveying band on an inclined plane 81, which should preferably be supplied with talcum or the like, in order that the printing of the ampullae may dry in a shorter time. At the discharge band 82 the ampullae are ready to be packed.

The ampullae are packed in an automatic packing device as shown in Fig. 26. The discharge band 82 of Fig. 24 slides along a band that is also rotating, or along a conveying device 84, on which are placed pasteboard wrappings 83. The latter may consist of the usual zig-zag shaped pasteboard strips, in the inter-spaces of which the ampullae are displaced through a shifting device 85 from the band 82 on to the band 84. The band 82 may be doubly provided, while the neck ends are lying opposite each other, so that the ampullae can simultaneously be inserted from both sides into the inter-spaces lying beside each other, the said shifting device 85 being arranged in such a manner that it will catch 12 ampullae on one side and 13 ampullae on the other, so that 25 ampullae are 115 inserted at the same time into each pasteboard wrapping. The arrangement may also be made in such a way as to provide, on the conveying device 84, folding surfaces 86 that are capable of 120 swinging round the joints 87. When a box of suitable dimensions is laid over the pasteboard wrapping after the ampullae have been inserted and the faces 86 are clapped round, the ampullae are lodged inside the box in a packing according 125 to instructions, whereupon the box may be filled out with wood wool or the like and closed with the lid.

What I claim is:

1. In an apparatus for filling and handling ampoules, a band-roll, said band-roll comprising coacting bands for holding a plurality of ampoules therebetween, a means for unwinding said band-roll, means for winding each of said coacting bands and means for removing said ampoules 135 from said coacting bands.

135

140

145

150

2. In a process for filling, sealing and handling ampoules the steps which comprise passing a plurality of said ampoules, in a row, individually spaced from each other, successively cutting and removing the tops from said row of ampoules, placing the said plurality of ampoules with their tops directed downwardly in contact with a filling liquid, filling said ampoules simultaneously by evacuating and admitting an inert gas to the filling liquid, centrifuging said plurality of ampoules, sealing the tops of the ampoules while moving them in an individually spaced row, and sterilizing them while in a position with their tops directed downwardly.
- 5 3. In an apparatus for filling and handling ampoules, a flat band-roll formed from a wound-up sheet metal band, and resilient means for fastening the ampoules between the windings of the band-roll.
- 10 4. In an apparatus for filling and handling ampoules, a band-roll formed from two flat wound-up sheet metal bands, and resilient means for fastening the ampoules between the windings of these two bands.
- 15 5. In an apparatus for filling and handling ampoules, a flexible sheet metal band provided with means for retaining a plurality of ampoules, means for inserting ampoules in said retaining means, and means for winding said band, filled with ampoules, into a roll.
- 20 6. In an apparatus for filling and handling ampoules, a flexible sheet metal band provided with means for retaining a plurality of ampoules, means for inserting ampoules in said retaining means, a second flexible sheet metal band cooperating with the first-named sheet metal band for firmly positioning said ampoules therebetween.
- 25 7. In an apparatus for filling and handling ampoules, a band-roll containing a plurality of ampoules, said band-roll comprising two co-acting bands with said ampoules held therebetween, means for unwinding said band-roll,
- 30 means for winding each of said bands thereby opening said band-roll, and means for removing the ampoules from said coacting bands.
- 35 8. In an apparatus for filling and handling ampoules, the combination of a sheet-metal band-roll holding the ampoules between the windings thereof, means for automatically delivering the ampoules from the band-roll to a container, the said container comprising a hollow cylinder having on its edge an aperture of the size of one ampoule, out of which the ampoules can pass separately to fall on a conveying band.
- 40 9. A device for handling a plurality of ampoules including a flexible sheet metal band, a plurality of resilient ampoule holding clips on said band, said band adapted to be wound in spiral form for holding said ampoules in said clips between the windings of the spirally wound band.
- 45 10. In an apparatus for winding and unwinding a sheet metal band to form a band roll between the windings of which a plurality of ampoules are held, a winding means, an unwinding means, a flexible sheet metal band positioned between said winding and unwinding means, a plurality of resilient ampoule holding clips on said band, and means for placing ampoules in said clips.
- 50 11. In an apparatus for unwinding and winding a sheet metal band to form a band roll between the windings of which a plurality of ampoules are held, a winding means, an unwinding means, a flexible sheet metal band positioned between said winding and unwinding means, a plurality of resilient ampoule holding means of said band, said holding means having an opening to one side to receive the ampoules, and a second sheet metal band co-acting with the first metal band to firmly hold the ampoules between two bands.
